LEAK-PROOF FOUNTAIN PEN

Bernard Grafton, Brooklyn, N. Y.

Application August 4, 1944, Serial No. 548,049

1 Claim. (Cl. 120—48)

1

The purpose of my invention is to provide a pen with a rotary valve structure, consisting of three cylindrical parts held in superposed relation by a rivet, the center cylinder valve alone being rotated in a manner that acts as a shutoff in the flow of the ink from the ink barrel to the pen point. This is a novel means of making the pen leak proof. This is accomplished by having the cap turn a cylinder which opens or closes the flow of the ink.

Referring to the drawing:

Figure 1 is a fragmentary view of the pen and cap.

Figure 2 is a sectional view on line 2—2 of Figure 1.

Figure 3 is a cross sectional view on the line 3—3 of Fig. 4.

Figure 4 is a sectional view on the line 4—4 of Fig. 3.

Figure 5 is similar to view shown in Fig. 3 showing segment turned part of a revolution.

Figure 6 is a cross section of line 6—6 of Fig. 5.

Figure 7 is a detail view, partly broken, showing pen point rest and ink channel.

Figure 8 is an end view of ink channel.

Figure 9 is outside view partly broken of portion of barrel of pen point holder.

Figure 10 is an end view of Fig. 9.

Figure 11 is a cross section of the cap showing projections and threaded portion.

I attain these objects by the means illustrated in the drawing accompanying this specification, in which 1 shows the entire pen; 2 is the cap of the pen; 3 shows the projections which set into the keyways of the revolving cylinder 4 and into the grooves 5; the cap shown as 2 has a thread shown as 6 which is turned onto the threaded portion shown as 7 of the body of the pen shown as 1. The 8 is the pen point rest showing the ink channel 9 through which the ink flows to the pen point 10; the pen rest is tapered so that it fits into the opening 10a of the pen shown as 1; the rivet 11 holds together part A as the pen point rest and pen point holder, with the revolving center cylinder part B which acts as the ink cut-off valve; part C is the barrel portion of the pen also held by rivet 11. A gasket is fitted at 12 into the grooves of A and B. The ink flows from the interior 13 of the barrel through the channel 9 in parts A, B and C. The gasket 14 is set in B and C into recesses which provide a seal against the leakage of the ink to the exterior and also acts as a tightening means between the parts C and B. The part B, which revolves around the rivet 11 also turns and closes

the channel 9 which passes through parts C and A. When the channel 9 is brought into a continuous straight alignment with parts A, B and C, a continuous flow of ink goes through the channel 9 from the interior of the barrel 13 into the opening, 10, of the pen as shown in Figure 3. The three projections 3 of the cap 2 set into the keyways which are a part of the cylindrical part B, shown at 5 and are spaced 120 degrees apart, or one third of the circumference interiorly within the cap; thus when the cap is screwed into the pen as shown at 6 and 7, the B cylinder is also caused to revolve and the ink channel in part B is turned away from the channels of A and C. The channel 9 is then closed as shown in Figure 5 by the turning of cylinder or part B. A gasket 15, is placed in the barrel part C, making this area moisture tight. The portion shown as 16 may be extended to enable an interior bladder for the ink to be sealed onto the said portion 16. The circular projections 17 shown in the Figures 3 and 5 fit into the circular recess 17a of the cylinder B. The circular projections 18 in Figures 3 and 5 fit into the circular recess 18a of the barrel C. The rivet shown as 11, is tightly held by a driving fit to the interior centers of parts A and C as shown in Figs. 3 and 5. The part B fits loosely on the rivet as shown in Figs. 3 and 5. Thus only part B is rotatable on the rivet.

To carry out the purpose of my invention, slight changes may be made in the construction of my leak proof pen without departing from the broad scope of my invention.

35 What I claim as new and useful is:

In a fountain pen, having three parts, said parts having a channel therethrough for the ink flow; a rivet passing through and holding together the parts in superposed relation; a center portion adapted to be rotated to open or close the valve around the rivet; said rivet holding together three divisions of the pen; turning the center portion by 120 degrees being sufficient to operate the valve; each of the three parts having a channel and the channels registering in one position of the part B and when part B is rotated, its channel going out of registry with the channel in each of the other two parts; a cap covering the pen which has three projections therein which extend into grooves of the center cylinder; said cap engaging the center portion and closing or opening the valve as the cap is screwed on or off respectively.

BERNARD GRAFTON.
